UNITED STATES PATENT OFFICE

ANTON SCHMID, OF HUNTINGTON, WEST VIRGINIA, ASSIGNOR OF TWO-THIRDS TO
HERBERT LANG, JAMES YERKESON, AND GRANT YERKESON, ALL OF HUNTINGTON,
WEST VIRGINIA

DEPTH CUT INDICATOR

Application filed December 31, 1929. Serial No. 417,789.

This invention relates to cut indicators for lathes and similar machinery and has for an object to provide a device for use in adjusting the tool to cut or turn a piece of work of 5 any desired depth and which will indicate the depth of cut while the work is being cut or turned.

A further object is to provide a cut indicator for lathes which will be of simple construction and convenient to manipulate and which will give micrometer measurements automatically of the depth of the cut.

With the above and other objects in view the invention consists of certain novel 15 tails of construction and combinations of parts hereinafter fully described and claimed, it being understood that various modifications may be resorted to within the scope of the appended claims without sacrificing any of the advantages or departing from the spirit of the invention.

In the accompanying drawings,

Figure 1 is a side elevation of the device, 20 Figure 2 is a plan view of the device with parts in section, taken on the line 2—2 of Figure 1,

Figure 3 is a detail view of the cam, on the line 3—3 Fig. 2,

Figure 4 is a detail sectional view taken on 25 the line 4—4 of Figure 2,

Figure 5 is a detail sectional view showing the micrometer bar and micrometer collar, and

Figure 6 is an end elevation of the parts 30 shown in Figure 5.

Referring now to the drawings in which like characters of reference designate similar parts in the various views, the numeral 10 designates the carriage of a lathe, the carriage being movable longitudinally on guides 40 11 through the instrumentality of a rack 12 and pinion 13 in the usual manner.

A cross slide 14 is mounted in guides 15 on the carriage and carries the usual compound slide 16 which supports the tool post 17 in which the cutting tool 18 is mounted. These parts are of the usual and well known lathe construction.

In carrying out the invention a pair of 45 brackets 19 and 20 are bolted or otherwise

secured as shown at 21 to the carriage 10. The bracket 19 is provided terminally with spaced bearings 22 and 23 and between these bearings with a bearing 24. The bracket 20 is provided terminally with a bearing 25 55 which is in alinement with the bearings 22 and 23 and in these alined bearings there is carried a tubular shaft 26. A cross feed shaft 27 is mounted at one end of the carriage 10 and is journaled in the bearing 24 of the 60 bracket 19. The cross feed shaft is provided at one end with the usual hand wheel 28 for manually operating the shaft and with a gear train indicated in general at 29 to which power may be applied through a gear 30 for 65 operating the cross feed shaft by power when desired. The opposite end of the cross feed shaft is equipped with a gear 31 which meshes with a gear 32 carried by a stub shaft 33 as 70 best shown in Figure 4. The stub shaft is mounted in suitable bearings 34 carried by arms 35 which extend downwardly from the bracket 19 and between the arms a worm 36 is mounted on the stub shaft and meshes with 75 a pinion 37 which is keyed to the above mentioned tubular shaft 26 and causes the latter to rotate when the cross feed shaft is turned. This tubular shaft through the instrumentality of a cam mechanism about to be described, 80 serves to move the cross slide 14.

A cam 38 is keyed to the tubular shaft 26 and is received between the branches of a forked bracket 41 which is integral with the cross slide 14. A roller 42 is adjustably mounted between the branches of the forked bracket by means of a yoke 43 and a set screw 44 as best shown in Figure 3 and rides upon the peripheral face of the cam. A pair of rollers 45 and 46 are carried by the terminals of the branches 39 and 40 and ride against the web of the cam and against the inner peripheral faces of the cam as shown. It is now clear that when the cross feed shaft 27 is turned, that the cam 38 will be moved and will move the cross slide 14 forward or backward 90 according to the direction of rotation of the cam.

In order that the movement of the cross slide may be measured and consequently the depth of the cut made by the tool measured 95

and indicated, the tubular shaft 26 is equipped with a gear 47 which meshes with a gear 48 carried on a stub shaft 49 which projects from the bracket 20, on this same shaft 5 there being keyed a gear 50 which meshes with a pinion 51. The pinion is keyed as shown at 52 to a sleeve 53 which is housed within the tubular shaft 26 and is equipped opposite the pinion 51 with a micrometer 10 collar 54.

A micrometer bar 55 is mounted to move longitudinally within the sleeve and is held against turning therein by a key 56 fixed to the side of the bracket 19 as best shown in 15 Figure 5. The micrometer bar extends through the micrometer collar at one end and at the opposite end is threaded as shown at 57, these threads engaging similar threads 58 formed on the inner face of the micrometer 20 sleeve 53 so that when this sleeve is turned through the instrumentality of the gears above described, the micrometer bar will be simultaneously moved longitudinally within the sleeve. The micrometer bar is provided 25 with graduations as shown in Figure 2 and also the micrometer sleeve is provided with graduations as shown in Figure 6, it being understood that the units may be read on the micrometer bar and the fractions thereof on 30 the micrometer collar in the usual manner. In the present embodiment of the invention, the micrometer collar is graduated into one hundred equal parts and the micrometer bar is graduated in inches, each inch being graduated 35 into ten equal parts. The micrometer bar is threaded ten threads to the inch.

In the present embodiment of the invention the above mentioned gear 47 carried by the tubular shaft 22 is provided with two 40 hundred teeth, the pinion 48 with twenty teeth, the gear 50 with two hundred teeth and the pinion 51 with twenty teeth. Other gear ratios may be employed to move the micrometer sleeve and the micrometer bar relative to each other.

It will now be clear that when the cross feed shaft 27 is turned that the tubular shaft 26 will be turned and will simultaneously move the cam 38 to move the transverse slide 40 14 and at the same time move the micrometer bar 55 and micrometer collar 54 to measure and indicate the extent of movement of the transverse slide 14, and cutting tool 18.

An indicator arm 59 is provided at one 55 end with a sleeve 60 which fits on the bearing 25 of the bracket 20. The indicator arm is provided terminally with a bearing 61 which receives a stem 62 of a head 63 which carries a disc 64. The face of the disc is in the exact 60 center of the lathe when the arm is rocked down to operative position as shown in Figure 1 and forms an abutment for the cutting edge of the tool for placing the tool accurately on the center line of the lathe. The 65 arm 59 may be swung back out of the way

after the tool is set as will now be described.

To set the tool 18 the indicator arm 59 is swung inward to the position shown in Figure 1. The compound slide 16 is then moved towards the indicator arm until the point 70 of the tool touches the disc 64 and the pointer of the head 63, which as shown, is at zero. The tool is now set for making a cut and the indicator arm 59 may be swung back out of the way. The cross feed shaft 27 may now 75 be turned to move the cross slide and tool carried thereby sufficiently to perform the desired depth of cut. Since the micrometer bar and the micrometer collar are simultaneously actuated during any movement of the cam 80 38 to actuate the cross slide, the depth of the cut will be indicated by these micrometer members.

The shape of the cam may be varied in accordance with whether the work to be cut or 85 turned is inside or outside work such as bottle molds, etc. By changing the ratio of the gear train indicated at 29, as will be readily understood, the tool may be actuated to cut a taper.

From the above description it will be readily seen that the micrometer bar and collar will indicate the exact depth of cut a tool is 90 making during the cutting operation and will automatically indicate any change in the depth of the cut.

It will be further understood that the device is applicable to other machines besides lathes and may be used on any type of machine employing cutting tools or operating 100 on any type of material, since the device contemplates in a broad sense, essentially the use of a cam for controlling the depth of a cut and an indicator synchronized with the movement of the cam and operating to continuously indicate the depth of the cut while it is being made.

It will be further understood that the cam shaft may be made solid and the cam graduated to read in conjunction with a vernier scale 110 if desired.

Having thus described the invention, I claim:

1. The combination with the carriage and the tool supporting cross slide of a lathe, of a cam carried by the carriage and actuating the cross slide, a micrometer bar slidable transversely of the cam and operatively connected to the cam for indicating the movement of the cross slide whereby to indicate the depth of cut made by the cutting tool, and means for simultaneously actuating the cam and the micrometer bar.

2. The combination with the carriage and the tool supporting cross slide of a lathe, of a tubular shaft, a cam on the tubular shaft for actuating the cross slide, a cross feed shaft for actuating the tubular shaft, a sleeve within said tubular shaft terminating in a micrometer collar, a micrometer bar slidable 125 130

longitudinally within said sleeve, means operatively connecting said sleeve and said tubular shaft and means operatively connecting said tubular shaft and said micrometer bar.

3. The combination with the carriage and the tool supporting cross slide of a lathe, of a cam carried by the carriage, a cross feed shaft for actuating the cam, a bracket on the cross slide, a roller on said bracket engaging the outer periphery of the cam, a roller on said bracket engaging the inner periphery of said cam, said rollers coacting in imparting movement of said cam to said cross slide, and a micrometer bar slidable transversely of the cam and operatively connected to be moved by the cam for indicating the movement of the cross slide whereby to indicate the depth of cut made by the cutting tool.

20 4. The combination with the carriage and the tool supporting cross slide of a lathe, a tubular shaft carried by said cross slide, of an arm pivoted on said carriage and adapted to be rocked towards the longitudinal center 25 of the lathe, and confront the tool carried by the tool holder, a head on said arm, a disc on said head adapted to form an abutment for the cutting edge of said tool for positioning the latter in the exact center of said lathe, a cam on said tubular shaft operatively connected to said cross slide for moving the cross slide, and a micrometer bar slidable through the tubular shaft and operatively connected to said cam for indicating movement of said cross slide whereby to indicate the depth of the cut made by the cutting tool.

5. The combination with the carriage and the cross slide of a lathe, of spaced brackets 40 carried by the cross slide, a tubular shaft journaled in said brackets, a cross feed shaft carried by one of said brackets, and geared to said tubular shaft, a cam disposed on said tubular shaft between said brackets, a bracket on said cross slide, means operatively connecting the cam to the last named bracket whereby the cross slide is moved when the cross feed shaft is actuated, and an indicating device operated by said tubular shaft for indicating the movement of said cross slide whereby to indicate the depth of cut made by the cutting tool.

6. The combination with the carriage and the cross slide of a lathe, of a tubular shaft 55 carried by said carriage, a cross feed shaft carried by said carriage for actuating the tubular shaft, a cam carried by said tubular shaft and operatively connected to said cross slide for moving the cross slide, a sleeve 60 within said tubular shaft terminating in a micrometer collar, a gear train operatively connecting said tubular shaft with said sleeve, and a micrometer bar housed within said sleeve and movable longitudinally thereof, there being interfitting screw threads

connecting the sleeve and the micrometer bar whereby when the sleeve is turned the micrometer bar is moved longitudinally thereof.

7. In a machine having a movable slide for 70 actuating a cutting tool to make various sizes of cuts, a cam for operating the slide, a micrometer bar slidable transversely of the cam and operated by movement of the cam for indicating the movement of said slide 75 whereby to indicate the depth of cut made by said tool, and means for simultaneously actuating said cam and said micrometer bar.

8. In a machine for making cuts in material, the combination of a cam for controlling the depth of the cut, and a micrometer bar slidable transversely of the cam and operated by the cam for indicating the depth of the cut while it is being made.

80 9. In a machine for making cuts in material, the combination of a cam for controlling the depth of the cut, a micrometer bar slidable transversely of the cam for indicating the depth of the cut, and means synchronizing the cam and the micrometer bar 90 for simultaneous operation.

In testimony whereof I affix my signature.

ANTON SCHMID. [L. S.]
